UNITED STATES PATENT OFFICE.

HENRY A. WHITFIELD, OF MONROE, LOUISIANA.

ADJUSTABLE NON-DETACHABLE TOP FOR BAGS, BASKETS, AND BARRELS.

1,146,605.

Specification of Letters Patent.

Patented July 13, 1915.

Application filed November 10, 1914. Serial No. 871,362.

To all whom it may concern:

Be it known that I, HENRY A. WHITFIELD, a citizen of the United States, and a resident of Monroe, in the parish of Ouachita 5 and State of Louisiana, have made an Improvement in Adjustable Non-Detachable Tops for Bags, Baskets, and Barrels, of which the following is a specification.

My invention consists in providing a top 10 or cover for use in bags, baskets, barrels and other like receptacles for holding their contents in place during shipment. I construct such top or cover in general conformity to the shape of the basket or other receptacle, 15 and of such size that it is adapted for vertical adjustment therein, and I secure it detachably in place at any required height above the bottom by means of cords, straps, or equivalents, the same being secured at one 20 end to the body of a receptacle at or near its bottom and at the other end to the top side of the top or cover.

The details of construction, arrangement, and combination of parts are as hereinafter 25 described, and illustrated in the accompanying drawing, in which—

Figure 1 is a vertical section of a basket provided with my attachment. Fig. 2 is a perspective view of the basket, together with 30 the adjustable top or cover above it. Fig. 3 is a perspective view of a portion of one of the cord or strap attachments.

In Figs. 1 and 2, A indicates the body of a basket and B my adjustable top or cover, 35 the same being constructed preferably of canvas, but may be made of wood, metal, or other thin material. The said top or cover is provided with a vertical pendent flange or rim b and it is made of such size that it may 40 be contained within the receptacle A and adjustable vertically therein so as to place it at different heights above the bottom according to the volume of the contents or articles contained in the receptacle.

Devices consisting of cords, strings, or straps are employed as means for securing the top or cover B in place; that is to say, upon the surface of the contents of the receptacle A. As shown in Figs. 1 and 2 rings 45 a are secured to the body of the receptacle A by means of loops a' formed of leather straps or other suitable material, at a point near the bottom thereof, and similarly rings b' are secured to the upper side of the top 50 or cover B. Cords, strings or straps C are attached to the rings a, and, when the top or

cover D is adjusted in place over the contents of the receptacle as shown in Fig. 1, the said cords or straps are passed through or otherwise attached to upper rings b' and 55 firmly tied or buckled in place. Thus the top or cover B is secured in place horizontally within the basket or other receptacle A, in such manner as to confine the contents so that the basket may be shipped, or handled 60 roughly without danger of escape or dislodgment of the contents.

It will be understood that while the cords or straps C are attached to the sides of the receptacle A near the bottom, they may instead be attached to the bottom itself; and, similarly, the upper ends of the cords or straps may be attached to rings on the flange or rim b of the cover D.

In many cases, it is desirable to secure 75 the top or cover B permanently to the body A of the receptacle, without, however, interfering with its adjustability. For this purpose I employ one or more supplemental ropes or straps C' applied as shown at the 80 left in Figs. 1 and 2. Thus, such rope or strap is passed through the ring a on body A and ring b' on top B, and other larger rings a² are secured permanently to the ends of such rope or strap.

It will be understood that the rope proper C' will have sufficient length and slack to permit the top B to be removed entirely from the receptacle A, in order to facilitate placing clothes or other things in the latter 90 or removing them therefrom, but without permitting complete separation of said parts A, B. When the top B is being applied, as shown in Fig. 1, the slack rope C' may be drawn up taut and the slack upper 95 portion of it allowed to lie on the top B.

The drawing illustrates but one permanent fastening for the top B, but in practice several may of course be employed. If desired, an ordinary top or cover may be provided for the receptacle, as shown in Fig. 1.

What I claim is:

1. A receptacle for the purpose specified consisting of a body having practically vertical sides, a top or cover formed of light 105 material and having a pendent rim, the same having a shape conforming to the receptacle in horizontal section and made of less dimensions than the receptacle, so that it is adjustable vertically therein, and flexible attachments secured to the sides of the receptacle adjacent to the bottom and adapted 110

for attachment to devices secured to the upper side of the top or cover, as described.

2. A receptacle comprising a body having vertical sides, a cover adapted to fit loosely therein, and having rings secured thereto, and means of permanent connection between body and top consisting of a slack rope of greater length than the height of said sides, the same being permanently secured to the

body and passing slidably through a ring ¹⁰ on the top and having a device secured to its upper end which prevents withdrawal from said ring, as described.

HENRY A. WHITFIELD.
